CLAIM

The ornamental design for a carbon dioxide adsorption device, as shown and described.

DESCRIPTION

FIG. 1 is a front, top, and left side perspective view of a carbon dioxide adsorption device showing our new design; FIG. 2 is a rear, top, and right side perspective view thereof; FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The evenly-spaced broken lines illustrate portions of the carbon dioxide adsorption device that form no part of the claimed design. The dash-dotted broken lines denote the boundary of the claim and form no part of the claimed design.
